UNITED STATES PATENT OFFICE

105,019

DESIGN FOR VENTILATED AWNING SHUTTER

Sidney A. Jones, Fort Lauderdale, Fla., assignor, by mesne assignments, to W. N. Alley, Incorporated, Wilmington, Del., a corporation of Delaware

Application June 17, 1936, Serial No. 63,350

Term of patent 14 years

To all whom it may concern:

Be it known that I, Sidney A. Jones, a citizen of Canada, but who has declared his intention to become a citizen of the United States, residing at Fort Lauderdale, county of Broward, State of Florida, have invented a new, original, and ornamental Design for Ventilated Awning Shutters, for which the following is a specification, reference being had to the accompanying drawing, forming a part thereof.

In the drawing:

The figure is a perspective view of the ventilated awning shutter in partly opened position.

I claim:

The ornamental design for ventilated awning shutter substantially as shown and described.

SIDNEY A. JONES.
